(57) **CLAIM**

The ornamental design for a drop tray, as shown and described.

DESCRIPTION

FIG. 1 is a top front left perspective view of a drop tray according to my new design;

FIG. 2 is a top plan view thereof;

FIG. 3 is front elevation view thereof;

FIG. 4 is a rear elevation view thereof;

FIG. 5 is a left side elevation view thereof;

FIG. 6 is a right side elevation view thereof;

FIG. 7 is a top plan view in an unfolded configuration; and, FIG. 8 is a top front left perspective view shown in use.

The broken lines depicting a highchair in FIG. 8 are for the purpose of illustrating environmental subject matter and form no part of the claimed design.

1 Claim, 6 Drawing Sheets
